SPECTACLES AND GLASSES PROTECTOR

Theo. J. Sowle, Algonac, Mich.

Application February 21, 1942, Serial No. 431,784

2 Claims. (Cl. 2-9)

This invention relates to improvements in protectors, and more particularly, to a spectacle and glasses protector.

The primary object of the invention is to provide a protector adapted to be used by athletes to protect spectacles and glasses worn by the athlete while playing strenuous games such as baseball and basketball.

Another object of the invention is to provide a protector as above which will deflect glancing blows from various angles without damaging the glasses or jarring the protector from its initial position.

Another object of the invention is to provide a protector embodying a semi-rigid frame composed of vertical and horizontal guard bars arranged so that the outlines thereof are conformative to the spectacles frame structure and will extend directly in front of the spectacles and longitudinally thereof and will allow peripheral vision.

Another object of the invention is to provide a light-weight, compact head gear for supporting the guard frame in a forwardly-spaced position directly in front of the wearer's eyes which is accomplished by a three-point suspension between the head gear and the guard.

Another object of the invention is to provide a protector which is fitted to the head and which is comfortable when worn and requires no adjustment to properly position the guard forwardly of the spectacles, all of which is accomplished by providing elastic gussets in the rear of the head gear so that the protector will automatically assume the correct shape.

Another object of the invention is to provide a protector including a light-weight head gear for supporting the guard member over a large supporting area extending from a point in front of each ear over the forehead and to provide a guard supported from these locations.

In the drawing:

Figure 1 is a front elevation of the invention showing the position of the guard relative to the head gear;

Figure 2 is a side elevation illustrating the protector applied to the head and showing the manner in which the guard extends in front of a pair of spectacles on the wearer;

Figure 3 is a top elevation showing in detail the cross straps of the skeleton head gear and the rectangular guard three point suspension;

Figure 4 is a fragmentary rear elevation looking in the direction of the arrows along the line

4-4 of Figure 2, showing in detail the elastic gusset in the head gear band;

Figure 5 is a vertical cross-section taken along the lines 5-5 of Fig. 2 looking in the direction of the arrows showing the padded construction of the head gear.

Because of defective vision many athletes find it necessary to wear glasses when engaged in active sports. The invention provides a protector which may be worn by athletes required to wear glasses and the protector includes a guard member positioned in front of the spectacles or glasses so that the wearer's vision will not be obstructed.

In general the protector comprises a relatively flexible skeleton head gear having a head-encircling band connected by an inserted elastic gusset so that the head gear will adjust itself to various head irregularities. The head-encircling band is provided with cross straps and depending ear pieces to provide a base of substantial rigidity when applied to the head. A chin strap connects the depending ear pieces to draw the head gear down snugly on the head.

Further, the protector includes a guard member comprising horizontal and vertical guard bars connected to the head gear by a three point suspension to prevent the guard, when struck a glancing blow, from being dislocated.

For the purpose of a more detailed description of the invention, attention is directed to the drawing wherein there is shown a preferred form of the invention and wherein the numeral 5 will generally be employed to designate a skeleton head gear, including a head-encircling portion 6 having side wing depending portions 7 which extend well along the sides of the head and are provided with ear openings 8.

In Fig. 2, the skeleton helmet 5 is shown in position for wear on a head as at H and the head-encircling portion 6 is shown as engaging and extending downwardly on the forehead F. The openings 8 allow free hearing and circulation of air around the ear E. Also, Fig. 2 illustrates the position of the spectacles S on the nose of the wearer with relation to the skeleton helmet and said spectacles are provided with the usual temple pieces T extending rearwardly and hooked over the ear as at E.

The skeleton helmet is provided with flexible cross straps 9 and 10 fastened at their point of intersection by means of a rivet 11 or the like.

Secured to the head-engaging side of the straps 9 and 10 is a lining 12 of soft flexible material such as soft leather, while the straps 9 and 10 are formed of a comparatively stiff leather, sub-

stantially identical to the material of which the head encircling portion 6 is formed.

An inner lining 13 is applied to the head encircling portion 6 and is formed of a relatively soft, flexible material such as leather and interposed between the head encircling portion 6 and the flexible lining is a resilient pad 14 formed of sponge rubber or similar cushioning material.

The cross straps 9 and 10 are stitched along their marginal edges as at 15 and the free ends of the cross strap 9 are interposed between the head encircling portion 6 and lining 13 so that the stitching 16 will anchor the same securely in place.

Similarly, the front end of the strap 10 is likewise anchored between the head encircling portion 6 and lining 13 by a row of stitching 16 while the rear end of the strap 10 is secured to elastic gussets 17 by being stitched thereto as at 18.

The head encircling portion 6 is interrupted in the rear as at 19, thus forming a small gap which is bridged by means of elastic inserts or gussets 17, the ends of which are sandwiched between the head encircling portion 6 and the inner lining 13 so that the same may be held in position by a row of stitches 16 and a vertical continuation thereof as at 20. The row of stitching 20 is continued along the lower edges of the head encircling portion 6 as at 21 and continues around the depending wing portions 7 as at 22 thence forwardly to the forehead portion as at 23 to securely fasten the lining 13 to the head encircling member 6. Likewise, the marginal edge of the opening 8 in each depending wing 7 is stitched as at 24.

Secured to the extreme forward portion of one of the depending wings 7 is a chin strap 25 the end of which is passed through a slot 26 and is then return bent so that it may be fastened by a rivet 27 to provide a looped end (Figs. 1 and 3).

The chin strap is passed under the wearer's chin and has its end passed through a slot 28 in the opposed depending wing 7 so that the free end may be looped through an adjusting buckle 29 by attachment to the center bar as at 30 and fastened by a rivet 31. The end loops 32 of the buckle slidably receive the chin strap whereby the loop extending through the slot 28 may be lengthened or shortened to adjust the chin strap and draw the skeleton helmet downwardly on the wearer's head.

Mounted on the forward portion of the skeleton helmet 5 is a guard frame generally designated by the reference character 33 and said guard extends forwardly and downwardly in front of the spectacles to defend and completely protect the spectacles against accidental blows directed thereon. The guard frame comprises upper and lower horizontal bars 34 and 35 having angular end portions 36 and 37 respectively connected at their ends by slightly curved bars 38. Intermediate the ends of the curved bars 38 there is provided a flattened apertured lug 39 adapted to be fastened to the depending wing of the skeleton helmet by means of an anchoring rivet 40.

Connecting the horizontal bars 34 and 35 and secured in place as by welding, is a series of vertical guard bars 41, preferably, there is a central-most bar connecting the intermediate portions of the bars 34 and 35 and a vertical bar for each end connecting the horizontal bars 34 and 35 while vertical bars 41 connect the angled end bars 36 and 37 adjacent the bends thereof. Various arrangements may be provided, and any number of

bars 41 may be used, so long as clear vision of the wearer is not obstructed.

Further, the guard 33 is braced against vertically directed and glancing blows by means of a pair of arcuately curved rearwardly extending bars 42 having their lower ends welded or otherwise secured at their juncture to the top horizontal bar 34 and the opposite ends are connected to a bar 43 parallel with the top frame bar 34.

Formed intermediate the ends of the bar 43 is a lug 44 which is adapted to be riveted as at 45 to the forehead portion of the skeleton helmet to anchor the guard at a third point thereby providing a three point suspension system to absorb and dampen shocks transmitted to the skeleton helmet 5.

When the protector is worn while playing strenuous games, the spectacle temple pieces T are engaged for a portion of their length as shown in Fig. 2 which aids in retaining the spectacles in position and holds them in the path of vision by reason of the added supporting surface.

After the protector has thus been positioned on the head, the guard 33 will extend in front of the spectacles S to ward off blows struck in the direction of the spectacles and defend the same against breakage or damage.

Preferably, the vertical guard bars 41 are placed on opposite sides of the spectacle lenses so as to allow the wearer an unobstructed peripheral vision and yet adequately protect the spectacles from damage and the resulting deleterious effects to the eyes.

A rectangular block or chunk of leather 46 is stitched to the gusset inserts 17 to connect the same and to fill the gap between the edges 19 of the head encircling portion 6.

While I have shown and described my invention in detail, it is to be understood that the same is to be limited only by the appended claims, for many changes may be made without departing from the spirit and scope of my invention.

What I claim is:

1. A spectacles and glasses protector comprising a guard frame, said frame consisting of a pair of relatively straight horizontal bars adapted to extend in front of the spectacles and bent at the ends of the spectacles to extend along the sides thereof, vertical frame bars connecting the horizontal bars at the intermediate and bent portions adapted to be positioned out of the range of vision of the spectacles, and a pair of spaced arcuately bent rearwardly and upwardly extending bar members connected to one of said horizontal bars for supporting the guard frame in front of the spectacles, said arcuate bent members being offset from the center of the guard frame and having means for attachment to a head gear having a head encircling band so that they will extend above the lenses of said spectacles, the bent portions of said straight horizontal bars extending along the sides of said spectacles having means for attachment to the side of said head gear to retain the guard positioned in front of said spectacles.

2. A spectacles and glasses protector for attachment to a head gear, comprising a rectangular guard frame including vertical guard bars for arrangement on opposite sides of the lenses of the spectacles, spaced horizontal frame bars connecting the vertical bars, said horizontal bars being bent to extend in front of and along the sides of the spectacles with their free ends connected to the sides of the head gear, and a central sup-

port secured to one of the horizontal bars for connecting the intermediate portion of said rectangular guard to the front of said head gear, said support comprising arcuately bent bar members extending upwardly and rearwardly from the rectangular guard frame to support the guard member in offset relation to the head gear and spec-

5 tacles and provide guard bars above the lenses of said spectacles, the bent portions of said straight horizontal bars extending along the sides of said spectacles having means for attachment to the side of said head gear to retain the guard positioned in front of said spectacles.

THEO J. SOWLE.
